CLAIM

The ornamental design for a handle hanger, as shown and
described.

DESCRIPTION

FIG. 1 is a top front isometric view of a handle hanger
showing a first embodiment of my new design;

FIG. 2 is a front elevation view of the design of FIG. 1, and
the rear view is a mirror image of the front view;

FIG. 3 is a right side elevational view thereof, and the left
side elevational view is a mirror image of the right view;
FIG. 4 is a top plan view thereof;

FIG. 5 is a bottom plan view thereof;

FIG. 6 is a top front isometric view of a handle hanger
showing a second embodiment of my new design;

FIG. 7 is a front elevation view of the design of FIG. 6, and
the rear view is a mirror image of the front view;
FIG. 8 is a left side elevational view thereof;

FIG. 9 is a top plan view thereof;

FIG. 10 is a right side elevational view thereof;

FIG. 11 is a bottom plan view thereof;

FIG. 12 is a top front isometric view of a handle hanger
showing a third embodiment of my new design;

FIG. 13 is a front elevation view of the design of FIG. 12,
and the rear view is a mirror image of the front view;

FIG. 14 is a right side elevational view thereof, and the left
side elevational view is a mirror image of the right view;
FIG. 15 is a top plan view thereof;

FIG. 16 is a bottom plan view thereof;

FIG. 17 is a top front isometric view of a handle hanger
showing a fourth embodiment of my new design;

FIG. 18 is a front elevation view of the design of FIG. 17,
and the rear view is a mirror image of the front view;
FIG. 19 is a right side elevational view thereof, and the left
side elevational view is a mirror image of the right view;

FIG. 20 is a top plan view thereof;

FIG. 21 is a bottom plan view thereof;

FIG. 22 is a top front isometric view of a handle hanger
showing a fifth embodiment of my new design;

FIG. 23 is a front elevation view of the design of FIG. 22,
and the rear view is a mirror image of the front view;

FIG. 24 is a right side elevational view thereof, and the left
side elevational view is a mirror image of the right view;
FIG. 25 is a top plan view thereof;

FIG. 26 is a bottom plan view thereof;

FIG. 27 is a top front isometric view of a handle hanger
showing a sixth embodiment of my new design;

(Continued)

FIG. 28 is a front elevation view of the design of FIG. 27, and the rear view is a mirror image of the front view; FIG. 29 is a right side elevational view thereof, and the left side elevational view is a mirror image of the right view; FIG. 30 is a top plan view thereof; FIG. 31 is a bottom plan view thereof; FIG. 32 is a top front isometric view of a handle hanger showing a seventh embodiment of my new design; FIG. 33 is a front elevation view of the design of FIG. 32, and the rear view is a mirror image of the front view; FIG. 34 is a right side elevational view thereof, and the left side elevational view is a mirror image of the right view; FIG. 35 is a top plan view thereof; and, FIG. 36 is a bottom plan view thereof.
